CLAIM

We claim the ornamental design for a housing for an autoinjector, as shown and described.

DESCRIPTION

FIG. 1 is a front perspective view of a housing according to our new design with the body being of indefinite length and constant cross-section between the break-lines;

FIG. 2 is a right side view thereof;

FIG. 3 is a front view thereof;

FIG. 4 is a rear view thereof;

FIG. 5 is a left side view thereof;

FIG. 6 is a top plan view thereof;

FIG. 7 is a bottom plan view thereof; and,

FIG. 8 is a rear perspective view thereof.
